(57) **CLAIM**

The ornamental design for a tire, as shown and described.

DESCRIPTION

FIG. 1 is a first perspective view of a tire showing my new design;

FIG. 2 is a second perspective view thereof;

FIG. 3 is a left side view thereof; and,

FIG. 4 is a front elevational view thereof.

In the drawings, the broken lines showing a tire inner bead depict the claim boundaries and form no part of the claim.
